UNITED STATES PATENT OFFICE.

JOHN M. TOBIAS, OF PITTSBURGH, PENNSYLVANIA.

DESIGN FOR A GAS-STOVE.

57,174.

Specification for Design. Patented Feb. 22, 1921.

Application filed May 19, 1920. Serial No. 382,608. Term of patent 14 years.

To all whom it may concern:

Be it known that I, JOHN M. TOBIAS, a citizen of the United States, residing at Pittsburgh, county of Allegheny, and State of Pennsylvania, have invented a new, original, and ornamental Design for a Gas-Stove, of which the following is a specification, reference being had to the accompanying drawings, forming a part thereof.

Figures 1 and 2 are views in perspective,

and from opposite sides, of a gas stove showing my new design.

I claim:

The ornamental design for a gas stove, substantially as shown.

JOHN M. TOBIAS.
